FILTER PROTECTION

William W. Martenis, Minneapolis, Minn., assignor to Minneapolis-Honeywell Regulator Company, Minneapolis, Minn., a corporation of Delaware.

Application January 24, 1938, Serial No. 186,565

15 Claims. (Cl. 126—110)

The present invention relates generally to warm air heating systems and pertains more particularly to the elimination of the fire hazard attendant to the use of combustible air filters in such systems.

In present warm air heating systems, it is customary to employ a fan for enforcing air circulation thus making possible the use of air filters for the purpose of removing foreign matter which 5 may otherwise contaminate the air stream. It is quite general also to employ an "economizer" which is a tortuous passage-way through which the gases of combustion pass on the way to the stack or flue. The "economizer" is arranged in 10 heat exchange relation with the return air so as to preheat it. As the trend in modern furnace design is toward placing all the elements associated with the furnace in as small a casing as possible in the interests of compactness and economy of space it is usual that the filters and economizer are located in close proximity in the 15 return air section of the furnace. The economizer temperature is rather high and particularly at times when the forced air circulation occasioned by the furnace fan fails there is grave danger of 20 igniting the filters which ordinarily are made of combustion material. The fire hazard is especially serious when the return air ducts are formed between wooden joists and flooring of 25 frame buildings. Furnace fan failure may occur as a result of the fan belt's breaking or failure of power to the driving motor. From experience it has been found that upon fan failure the economizer temperature quickly rises to a temperature 30 at which ignition of the filter material may take place. Failure of power for the fan motor is decidedly serious in the case of coal-fired hot air furnaces inasmuch as the fire continues after the 35 fan stops and the economizer temperature quickly 40 rises to the danger point.

It is the above described serious fire hazard attendant to the use of filters in furnace fan warm air heating systems which it is the primary objective of my invention to overcome.

45 Among other objects of my invention is to provide positive means for isolating the filters from the furnace in a warm air heating system whenever the forced air circulation occasioned by the furnace fan fails.

50 Another object is to provide a damper closing device in the return air chamber between the filters and the furnace in the above described system, the damper device to be held open only when forced circulation is being provided by the 55 fan. Concurrently with this object it is a further

object to provide a power failure motor for operating the damper device arranged to cause closing of the damper device whenever the motor is deenergized.

It is another object of the invention to control the power failure motor referred to in the previous object from a sailswitch located in the path of the enforced air circulation.

Other objects and purposes of the invention will become apparent from an examination of the 10 drawing and the more detailed description following.

The single figure of the drawings represents somewhat diagrammatically a warm air heating system having my invention incorporated therein. 15

Referring to the drawing, numeral 10 represents generally a furnace casing forming part of a warm air heating system having conduits 11 and 12 for conveying air to and from the casing of the furnace respectively. The conduits 12 and 20 11 may have branch conduits 13 and 14 as shown for conveying air to and from various rooms of a building as shown. The furnace casing 10 is divided into three separate compartments or chambers designated 16, 17, and 18. The chamber 16 25 houses an electrically driven oil burner 19 of conventional type and located within the chamber 17 is a furnace or combustion chamber proper 20 which serves to heat the air within the chamber 17. The nozzle of the oil burner 19 extends from 30 the chamber 16 through the chamber 17 and into the combustion chamber 20. The oil burner 19 has electrical terminals 22 and 23 which connect to electrical conductors for supplying power to the oil burner. Within the combustion chamber 35 20 and adjacent the end of the nozzle of the oil burner is located a pipe 24 communicating with a supply of gas whereby a pilot flame 25 may be kept constantly burning for igniting the fuel from the oil burner whenever the burner is to be put 40 into operation. Located adjacent to the pilot flame 25 so as to be heated thereby is a bimetallic 45 thermostatic element 26 forming with contact 27 an electrical switch serving as a safety device to shut off the oil burner whenever the pilot flame 45 should become accidentally extinguished. The control instruments and wiring of the apparatus will be presently described.

The chamber 18 of the furnace casing forms a return air chamber through which the cooler air 50 from the spaces being heated is passed before being forced over the furnace or heating chamber 20 itself. The burnt gases of combustion from the furnace are passed through a tortuous passage-way in the economizer 21 which is located

in the path of the return air chamber 18. Heat from the burnt gases of combustion is therefore given off to the return air and serves to preheat the return air on its passage through the furnace casing. The end of the tortuous passage-way in the economizer 21 communicates with a pipe 30 which serves to convey the burnt gases of combustion to a conventional stack or flue. The return air chamber 18 of the furnace casing includes a portion 31 within which are located filters 32 for removing impurities such as dirt and dust with which the air may have become contaminated in the spaces being heated. The filters comprise slabs of any suitable material which will filter out or remove impurities from the air without substantially obstructing the passage of air therethrough. The slabs 32 of filter material are supported between supporting members 33 and the walls of portion 31 of the furnace casing. It will be noted that portion 31 has an internal dividing wall 34 which divides it into two portions, the upper end of one of the slabs 32 resting against this internal dividing wall. By reason of the arrangement of the filters they may be removed at will from the furnace casing and replaced by new ones whenever they have become unduly fouled with foreign matter from the stream of air passed thereover. The return air from the spaces being heated is conveyed through conduit 11 through the portion 31 of the return air chamber and past the economizer 21 to be preheated on its way through the return air chamber. At the lower part of the return air chamber is a fan or blower 36 which draws in air from the return air chamber and forces it through a conduit 37 through the air heating chamber 17 to conduit 12 and thereby providing a forced circulation of air in the entire system. The fan 36 is of conventional type and is driven by an electric motor 37 through a belt 38 or other similar drive means.

Positioned so as to be affected by the circulation of the air in the discharge conduit 37 of the fan is a member 40 pivoted at 39 having a mercury switch 41 located at the upper end thereof. The elements 40 and 41 form a sailswitch which is closed whenever the enforced circulation of air in the discharge conduit 37 causes the lower part of the member 40 to be moved to the left so that the mercury in the switch 41 engages the electrodes therein.

Positioned between the filter members 32 and the economizer 21 in the return air chamber 18 are a plurality of louvre members 45 forming a damper for closing off the circulation of air which normally passes over the filter members and thence over the economizer. The louvre members 45 are pivotally connected to an operating link 46 so as to be moved in the conventional manner in which dampers are operated. The link 46 is connected by another link 47 to a rack 48 driven by a pinion 49. The pinion 49 is driven by a shaft 50 connected to an electrical damper motor 51 which may be of a conventional type. The damper motor 51 has electrical terminals 53 and 54 for connecting to electrical conductors for supplying power to the damper motor. The damper operating link 46 has pivoted thereto a lever 56 the opposite end of which is pivoted to a link 57 which is connected to a coil spring 58 which causes the lever 56 to be biased in a clockwise direction. When the link member 46 has been moved to the right sufficiently to position the louvre members 45 vertically the lever 56 engages a suitable stop member 60. In normal

operation the damper motor 51 is energized and through pinion gear 49 and rack 48 retains the link 46 in its extreme right-hand position with the lever 56 engaging stop 60 and the louvres in vertical position. In this position the spring 58 is under tension and should motor 51 become deenergized the spring will move lever 56 in a clockwise direction and close the dampers by moving the louvres 45 into a horizontal position.

The heating system is primarily controlled by a thermostat generally indicated at 63 which may be located in one of the rooms being heated. The thermostat is of conventional type comprising a circularly arranged bimetallic element 64 connected to a movable arm 65 having a switch contact 66. The switch contact 66 is arranged to make or break an electrical circuit through a fixed contact 67. The system is additionally controlled by mercury switches 68 and 69 which are operated by a thermostatic element 70 of the helical type arranged to be responsive to the temperature of air being heated within the chamber 17. The thermostatic element 70 is adjusted so as to cause switch 69 to close the circuit therethrough at a predetermined temperature within the chamber 17. Switch 68 is normally closed and is opened by element 70 at a predetermined relatively high temperature.

Referring to the electrical wiring connecting the various devices included in the system and the instruments for controlling them, numerals 72 and 73 indicate line conductors connected to an external source of power (not shown). The line conductor 73 is connected by a wire 74 to the motor 37 for driving the fan 36. The circuit to the motor 37 is completed by wire 75 which connects the motor to the switch 69 and the wire 76 which connects switch 69 to the line conductor 72. It will be seen therefore that whenever the thermostatic element 70 causes switch 69 to close, motor 37 operating the fan will be put into operation enforcing the circulation of air through the system.

The electrical circuit for providing power for the oil burner 19 is supplied through a wire 80 connected to the wire 74, a wire 81 which connects the oil burner to the thermostatic switch 26, a wire 82 connecting the thermostatic switch to the mercury switch 68, a wire 83 connecting the mercury switch 68 to the thermostatic switch 63 and a wire 84 connecting the latter switch to the line conductor 72. It will be seen that power is supplied to the oil burner through the above described circuit whenever the switches 26, 68, and 63 are in closed position. Switches 26 and 68 are normally closed and the burner circuit is complete whenever the switch formed by the thermostatic device 63 is closed. Switch 26 acts as a safety device breaking the burner circuit whenever the pilot flame 25 should for some reason become accidentally extinguished and switch 68 acts as a high limit operating to break the burner circuit whenever the temperature in chamber 17 exceeds a predetermined relatively high value. Thus the switches 26 and 68 shut down the system in the event of the temperature becoming too high or in the event of pilot flame failure thereby preventing fuel being forced into the combustion chamber when there is no means of igniting the same and causing consequent danger of explosion.

The circuit for providing electrical energy for operating the damper motor 51 is formed by a connection from line conductor 72 to terminal 54 of the motor, a wire 87 which connects to the

mercury switch 41 and a wire 88 which connects to the wire 74. Thus it will be seen that the damper motor 51 is energized so as to cause the dampers to be open whenever enforced circulation of air in discharge conduit 37 of the fan has closed the sailswitch 41. In normal operation considerable heat is radiated from the economizer 21 which tends to heat the air in chamber 18 and also to raise the temperature in the portion 31 of chamber 18. When the fan is in operation air is continually circulated through the chamber 18 carrying the heat from the economizer into chamber 17 and preventing the temperature in chamber 18 from rising unduly high. In conventional arrangements of this type whenever the fan stops the radiation of heat from the economizer 21 tends to raise the temperature adjacent the filters 32 to a relatively high value at which there is danger of their becoming ignited and causing danger of fire. In my arrangement whenever the fan 36 stops for any reason the switch 41 is open and the motor 51 becomes de-energized causing the dampers 45 to close. Likewise dampers 45 close whenever there is a failure of the supply of power to motor 51. Closure of the dampers isolates the filters 32 from the economizer and obstructs the transfer of heat by radiation from the economizer to the filters. Positive assurance is therefore provided that the temperature adjacent the filters will not rise to a high enough value to cause danger of their becoming ignited.

From the foregoing the operation of the apparatus described should be apparent to those skilled in the art. With the parts in the position shown the room temperature has fallen to a low enough value so that the thermostatic device 63 has closed the circuit thus calling for heat to be supplied to the room. The oil burner 19 has been started through the circuit above described. When the temperature in chamber 17 has risen to a predetermined value switch 69 closes. Closure of switch 69 causes operation of the fan 36 and the pressure of the air in the discharge conduit 37 causes closure of switch 41. Closure of this switch energizes the damper motor 51 causing the dampers 45 to be opened. Positive circulation of the air will now continue until the room thermostat becomes satisfied at which time the burner circuit will be broken. The temperature within chamber 17 will then fall to a predetermined value at which switch 69 will open thus deenergizing the fan motor. Upon the fan stopping switch 41 will open and damper motor 51 will be deenergized permitting the dampers 45 to be closed by the spring 58. It will be seen that at any time during which heat is being supplied to the rooms should the fan 36 be stopped due to power failure or the breaking of the belt or the like, the dampers 45 will be closed preventing the temperature adjacent filters 32 rising to an unsafe value. Should switch 69 fail to close upon a rise in temperature in the chamber 17 when the room thermostat is calling for heat, the fan motor 37 will not be energized and consequently the dampers 45 will not open. It is apparent therefore that my device insures that at all times the filters provided within the furnace casing will be protected from temperatures which may cause them to ignite and thereby set fire to the building. The safety features involved eliminate a very serious fire hazard present in a large number of heating systems

and the results are accomplished by a positive acting and easily installed device.

Having disclosed one embodiment of my invention it is to be understood that this disclosure is to be interpreted as illustrative only and the invention is to be limited only as determined by the appended claims.

I claim as my invention:

1. In a warm air heating system, in combination, means for heating air, means for enforcing circulation of air to and from said heating means, filter means for cleaning the circulating air exposed to heat from said heating means and means responsive to failure of the air circulation enforced by said circulation enforcing means for isolating said filter means from said heating means. 10

2. In a warm air heating system, in combination, means for heating air, means forcing air to circulate to and from said means, filter means for cleaning said air exposed to heat from said heating means, means for isolating said filter means from said heating means, said isolating means being controlled by the forced air circulation provided by said air forcing means so that said filter means becomes isolated from the heating means whenever the forced air circulation fails. 20

3. In a warm air heating system, in combination, air heating means, means for positively circulating air past said heating means, filter means for cleaning said air exposed to heat from said heating means, means responsive to temperature of air being heated to control said air circulation means and means controlled in response to the circulation of air for isolating said filter means from the heating means whenever positive air circulation fails. 30

4. In a warm air heating system, in combination, an air heating means, duct means providing for circulation of air past said air heating means, filter means for cleaning air exposed to heat from said heating means, means operable between open and closed positions for closing off air circulation past said heating means and isolating said filter means from the heating means, means for enforcing air circulation in said duct means and means energized in response to forced air circulation for maintaining said closing means in open position, said energized means becoming deenergized whenever forced air circulation fails whereby said closing means closes. 40

5. In a warm air heating system, in combination, a furnace, duct means for conveying air to said furnace and a fan for positively circulating air past said furnace, filter means adjacent said furnace and damper means between said filter means and said furnace, motor means operable when energized to maintain said damper means in open position, means comprising a sailswitch 55 responsive to the air circulation controlling said motor means so that said motor means is deenergized when the air circulation does not close said sailswitch. 60

6. In a warm air heating system, in combination, a furnace having a casing including a return air chamber, an economizer in said return air chamber and air filter means located adjacent said economizer, damper means between said filter means and economizer for isolating the filter 70 means from the economizer, means for enforcing air circulation through said casing and means responsive to said enforced air circulation for controlling said damper means. 70

7. In a warm air heating system, in combina-

- tion, a furnace having a casing, means for circulating air to be heated through said casing, means providing heat exchange relation between burnt gases of combustion and air to be heated in said casing, filter means for cleaning the air located in said casing and means comprising a sailswitch responsive to the air circulation for isolating said filter means from said heat exchange means at a predetermined rate of air circulation whereby the temperature adjacent said filter means cannot become excessive.
8. In a warm air heating system, in combination, a furnace, means for circulating air to be heated to and from said furnace, means forming part of said furnace for preheating the air circulated to said furnace, filter means for cleaning the air circulated to said furnace, means for shielding said filter means from radiant heat from said preheating means, means comprising a sailswitch responsive to the air circulation controlling said shielding means and arranged to cause said shielding means to be moved into shielding position at a predetermined rate of air circulation whereby the filter means are protected from overheating.
9. In a warm air heating system, in combination, a furnace, means comprising a fan for forcing air to be heated past said furnace, said furnace having a return air chamber, an economizer comprising a tortuous passageway for burn gases of combustion located so as to be in heat exchange relation with the return air passing through said chamber, air filter means located adjacent said economizer, means for obstructing radiant heat flow between said economizer and said filter means, and means comprising a sailswitch and a motor controlled thereby responsive to the air forced by said fan for moving said obstructing means out of obstructing position when said sailswitch is closed.
10. In a warm air heating system, in combination, means for heating air, means for circulating air to and from said heating means, filter means for cleaning the circulating air exposed to heat from said heating means, and power controlled means operable upon failure of the power supply for isolating said filter means from said heating means.
11. In a warm air heating system, in combination, means for heating air, means for circulating air past said heating means, filter means for cleaning said air exposed to heat from said heating means, means interposed between said filter means and heating means for isolating said filter means from heat, said interposed means being power controlled and assuming isolating position whenever power is not supplied thereto.
12. In a warm air heating system, in combination, means for heating air, means for circulating air past said heating means, air filter means for cleaning said air exposed to heat from said heating means, and power controlled means operable upon failure of power supply thereto to abruptly interpose a heat protective medium between said filter means and heating means.
13. In a warm air heating system, means for heating air, means for enforcing air circulation past said heating means, filter means for cleaning said air exposed to heat from said heating means, means interposed between said filter means and heating means to protect the filter means from overheating, and control means for said interposed means comprising power operated means responsive to failure of the enforced air circulation to cause isolation of said filter means by said interposed means, said power operated means also being responsive to power failure for causing isolation of the filter means.
14. In an air heating system, in combination, means for heating air, means for circulating air over said heating means, filter means for cleaning the circulating air exposed to heat from said heating means, said filter means being susceptible to becoming overheated, and means responsive to a condition indicating that the said filter means may become overheated for isolating said filter means from said heating means.
15. In an air heating system, in combination, air heating means, duct means providing for circulation of air past said air heating means, filter means for cleaning air exposed to heat from said heating means, said filter means being susceptible to becoming overheated, means operable between open and closed positions for closing off said duct means and isolating said filter means from said heating means, means for enforcing air circulation through said duct means, and means responsive to a condition indicating danger of said filter means becoming overheated for causing said means operable between open and closed positions to assume a closed position isolating said filter means from said heating means.

WILLIAM W. MARTENIS.
